UNITED STATES PATENT OFFICE.

FREDERICK W. HOCHSTETTER, OF NEW YORK, N. Y., ASSIGNOR TO PAUL M. PIERSON,
OF SCARBORO-ON-THE-HUDSON, NEW YORK.

COMPOSITION OF MATTER FOR RESTORING THE PICTURES ON FILMS.

1,139,682.

Specification of Letters Patent. Patented May 18, 1915.

No Drawing.

Application filed October 7, 1913. Serial No. 793,892.

To all whom it may concern:

Be it known that I, FREDERICK W. HOCHSTETTER, a subject of the Emperor of Germany, and a resident of New York, county and State of New York, have invented a certain new and useful Composition of Matter for Restoring the Pictures on Films, of which the following is a full, clear, and exact specification.

10 This invention relates to a modified composition of matter disclosed in my pending applications for Letters Patent, Serial Number 732,465, filed November 20, 1912, Serial Number 770,177, filed May 27, 1913, Serial Number 771,689, filed June 4, 1913, Serial Number 774,864, filed June 20, 1913, and Serial Number 785,091, filed August 16, 1913.

My invention has for its object primarily 20 to provide a composition of matter designed to be employed for restoring the pictures of moving picture films when the texture of the film has become hardened, and the photographic pictures thereon have been impaired by scratches and the collection of 25 particles of dust or other foreign substances after being transmitted a number of times through a projecting machine; the said composition being adapted to free the crevices 30 of the scratches of all accumulated foreign matter as well as serving to clear the high lights and the shadows of the photography of the pictures, and also serving to soften the texture of the film for restoring its flexibility. Thus moving picture films which 35 usually become practically worthless after being used a few times may be restored sufficiently so that the pictures thereof may be exhibited many times as occasion requires.

The composition of matter consists of the following ingredients, combined in the pro-

portions stated, viz:—a fatty base, such as lard, tallow, bees wax, paraffin, spermaceti, petrolatum, or any suitable animal, vegetable, or mineral fat 45 6 ounces; alcohol (U. S. P. strength) by weight 2 ounces.

The alcohol is thoroughly incorporated in the fatty base by any suitable means, and the composition is applied to the surfaces of 50 the moving picture film by the employment of a pad of chamois skin, or other soft material until a coating is formed thereon. The coating on the film is then frictionally rubbed by the use of the pad, or otherwise 55 to soften the texture of the film for restoring its flexibility and until the crevices of the scratches have been thoroughly penetrated. By subsequently freeing the film of 60 all surplus of the coating the foreign substances in the photography of the pictures and the foreign substances in the scratches will be entirely removed so that the transparency of the film and the high lights and shadows of the pictures will be restored. In 65 this manner moving picture films which usually become practically worthless after being used a few times may be restored sufficiently so that the pictures thereof may be exhibited many times. 70

Having thus described my invention, I claim as new and desire to secure by Letters Patent:—

A restorative for moving picture films comprising a fatty base six ounces, and alcohol two ounces, substantially as described. 75 and for the purpose specified.

This specification signed and witnessed this sixth day of October A. D. 1913.

FREDERICK W. HOCHSTETTER.
